FISH BOWL

James J. Edwards, High Point, N. C.

Application November 19, 1951, Serial No. 17,469

Term of patent 7 years

(Cl. D91—2)

To all whom it may concern:

Be it known that I, James J. Edwards, a citizen of the United States, residing at High Point, county of Guilford, and State of North Carolina, have invented a new, original, and ornamental Design for Fish Bowl, of which the following is a specification, reference being had to the accompanying drawing, forming a part thereof.

I claim:

The ornamental design for a fish bowl, as shown.

JAMES J. EDWARDS.
